COMBINED TRAVERSE ROD AND CARRIERS

Warren B. S. Cameron, 33 Aviation Ave.,
Hillsgrove, R.I.

Filed July 17, 1959, Ser. No. 56,829

Term of patent 14 years

(Cl. D21—1)

FIG. 1 is a perspective view of a combined traverse rod and carriers showing my new design;

FIG. 2 is a top plan view on reduced scale of the overlapping master carrier seen at the right of FIG. 1;

FIG. 3 is a front elevational view thereof;

FIG. 4 is an end elevational view as seen from the right thereof;

FIG. 5 is a top plan view of the plain master carrier seen at the left of FIG. 1;

FIG. 6 is a front elevational view thereof; and

FIG. 7 is an end elevational view thereof.

The essential features of my design reside in the portions shown in solid lines on the drawing.

I claim:

The ornamental design for a combined traverse rod and carriers, as shown and described.
